Primary Examiner — Sandra S Snapp*Assistant Examiner* — Katherine Glennon(74) Attorney, Agent, or Firm — Blank Rome LLP(57) CLAIM

The ornamental design for a watch, as shown.

DESCRIPTION

FIG. 1 is a front right perspective view of a watch showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear left perspective view thereof.

The inner portions of the rear of the watch depicted in broken lines form no part of the claimed design.

1 Claim, 5 Drawing Sheets(56)
